UNITED STATES PATENT OFFICE.

HARLAN SMITH HOWARD, OF MADISON, WISCONSIN.

PULVERIZER.

SPECIFICATION forming part of Letters Patent No. 440,036, dated November 4, 1890.

Application filed August 13, 1888. Serial No. 282,596. (No model.)

To all whom it may concern:

Be it known that I, HARLAN SMITH HOWARD, a citizen of the United States, residing at Madison, in the county of Dane and State 5 of Wisconsin, have invented certain new and useful Improvements in Pulverizers for Mel-lowing Fall-Plowed Land and Sod, of which the following is a specification, reference being had therein to the accompanying drawings.

This invention relates to improvements in machines for pulverizing ground; and it consists of an adjustable frame, hereinafter described, and pulverizing-teeth of peculiar construction.

In the drawings, Figure 1 is a plan view of the entire machine. Fig. 2 is a vertical section on the line $x-x$, Fig. 1. Fig. 3 is a partial rear view. Fig. 4 is a side elevation of one of the beams and one of the teeth or blades attached thereto. Fig. 5 is a front edge view of one of the teeth or blades. Fig. 6 is a side elevation of one of the blades. Fig. 7 is a section on the line $y-y$ of Fig. 6. Fig. 8 is a side view of one of the adjustable clamps for the blades. Fig. 25 9 is a face view of a washer used with the blade-clamp. Fig. 10 is a detail view of a bracket.

Referring to the drawings, A designates the axle-beam, carrying brackets B at each end. 30 Each bracket is provided with a seat b for a forwardly-extending timber C and a spindle b' for the wheel D, the said spindle being formed on or secured to the lower end of the said bracket, so that the beam A and brackets 35 B form an arched axle.

To the forward end of the timbers C, which are rigidly connected to the beam A by the brackets B, is pivotally secured a transverse beam E, to which latter is pivoted a series of 40 beams F for pulverizing-teeth G, hereinafter referred to. The pivotal connections between the beam E and beams F consist of brackets H.

Centrally on the beam E is erected a standard I, provided with holes i. This standard pivotally supports a pole K by means of a bolt k, the holes i permitting suitable vertical adjustment. The pole extends rearwardly from the standard, and near its rear end is 50 connected pivotally to a transverse beam L by means of a bracket l.

The beam L is parallel to the beam E and carries, pivotally, the forward ends of a series

of beams M, carrying pulverizing teeth or blades G. The beams M alternate with the 55 beams F and extend farther rearward.

To the beams E and L are rigidly secured rearwardly-extending timbers N, carrying at their rear ends a transverse timber O, above the beams F M, and forming a pressure-bar, 60 as will presently appear.

The pressure-bar O is provided with a series of holes through which pass headed bars or rods P, connected to the beams F M and surrounded by springs R between said beams 65 and the said pressure-bar. Flat or other shaped springs may be used. As is evident, the spring-surrounded rods P form yielding supports for the rear ends of the beams F M, so the teeth G may readily pass obstructions. 70

S designates the seat-supporting timber pivoted to and extending on each side of the axle A. The front end of the said timber S is pivotally connected to the pole or tongue K, so that the driver's weight will in a measure counterbalance the weight of the pole and machine. On the axle A, adjacent to the timber S, is a rack-plate T for engaging a hand-lever U, connected to the rear end of the pole by a link V. The hand-lever and 80 rack may be of any suitable construction. 75

In Fig. 2 the parts are shown in the raised position. If now the lever be moved, the rear end of the tongue will drop, the horses' necks being the fulcrum. The cross-beams E and 85 L, being connected to the pole, will also fall, and the whole frame will move on the wheel-spindles as a center, since the beam E is pivotally connected to the timbers C and the latter are secured to move with the axle A. 90 This operation will be at once apparent from an inspection of the drawings.

I will now proceed to describe the teeth or blades and the connections to the beams, as shown in Figs. 4 to 9, inclusive. The teeth or 95 blades G each consist of a shank A', a main or body portion B', and a bent or angular portion C'. The body B' and angular portion C' have one edge sharpened throughout, and the other edge is preferably thickened to 100 strengthen the blade. As will be seen from Fig. 5, the body portion may be at an angle to the shank, and the angular portion C' is slightly twisted, as shown more clearly in Figs. 6 and 7.

When in operation, the body portion of the 105

blade presents a knife-edge in the direct line of draft and offers but the minimum of resistance to the passage of the blade through the ground. The angle portion C', however, presents the cutting-edge at an angle approximating forty-five degrees to the line of draft and about the same angle to the vertical, with the said cutting-edge directed downward and rearward.

10 It will be seen that the relative angle of the portion C' to the vertical may be varied by adjusting the angle of the body portion to the beam. The shape and angle of the portion C' tends to force the tooth or blade into the ground; but being restrained by the frame the earth is lifted and caused to flow over the said portion, being thereby pulverized. It is to be noted that the earth is not turned over, as is done by a plow, but is lifted only—an 15 action which has been found to readily disintegrate all lumps. The sharpened body permits the tooth to be sunk deep into the ground.

10 The special object I have in view in constructing the pulverizing-teeth in the peculiar manner shown and set forth is to compel or force them to automatically sink deep into the soil when the machine is drawn along over the surface of the ground, and thus provide 25 for the deep and thorough cultivation and pulverization of the same. The special advantage of this construction of tooth is that this "deep" cultivation and pulverization is thoroughly accomplished with the least 30 amount of resistance and without turning over the soil, thus permitting of the use of a comparatively light frame and harness.

Each tooth is secured to its respective beam by a casting. (Shown in Fig. 8.) This consists 40 of a bracket D' with a central bolt-hole, and a segmental off-set E', having a roughened or toothed face to receive a similarly-constructed washer F'. (Shown in Fig. 9.) The casting is secured to the beam by two bolts, one of which 45 passes through the shank A' of the tooth and the bolt-hole in the body of the bracket, and the other through the washer F' and the segment E'. The body D' is so constructed as to receive the shank A' and hold the same at 50 an angle, as shown, while the segment permits the adjustment of the bracket around the bolt holding the blade, the corrugations preventing further movement when adjusted.

I prefer to have one blade to each beam, 55 with the blades on one side of the machine turned in a direction opposite those on the other side, as plainly shown in Fig. 1. It will be seen that the angle of the blade or tooth to both the vertical and horizontal is 60 such that should it encounter an obstruction it will move upward and ride over the same, the rod P and spring R permitting such movement.

I do not confine myself to the exact construction and arrangement of parts shown, 65 but may vary the same without departing from the spirit of my invention.

Having described the invention, what I claim is—

1. A pulverizer consisting of a pivoted 70 frame, a transverse beam pivoted thereto, tooth-carrying beams pivoted to said transverse beam, a tongue or pole connected to said beam, another transverse beam also connected to the pole, tooth-carrying beams pivoted to the latter transverse beam and alternating with the other tooth-beams, and means, 75 substantially as described, for adjusting the frame and beams, as set forth.

2. The combination, in a cultivator and pulverizer, of a pivotally-supported frame, a transverse beam pivotally connected to this frame, tooth-carrying beams pivoted to this transverse beam, rearwardly-extending beams N, connected to the said transverse beam, a 85 pressure-bar supported upon these beams N, yielding connections between the pressure-bar and tooth-beams, and means for adjusting the said parts, substantially as described.

3. The combination of the axle-beam supported upon transporting-wheels, forwardly-extending beams C, rigidly connected to the axle-beam, a transverse beam E, pivotally connected to the said beams C, a pole or tongue pivotally connected to this beam E, 95 another transverse beam L, pivotally connected to the tongue, tooth-carrying beams pivotally connected to the said beams E and L, rearwardly-extending beams N, supported upon the transverse beams E and L, a pressure-bar O, supported upon the beams N, yielding connections between the pressure-bar and tooth-beams, tooth-beams, and means for adjusting the parts.

4. The combination of a pivoted frame supported upon wheels, a transverse beam hung to this frame, beams hung to this transverse beam and provided with cultivating means, the tongue pivotally connected to this transverse beam, a beam S, supported upon the 105 axle of the frame and pivotally connected at its forward end to the tongue, this beam carrying the driver's seat, and a lever pivotally supported on the frame and connected to the rear end of the tongue, substantially as described.

5. The combination of a pivoted frame mounted upon wheels and provided with forwardly-extending arms, a transverse beam hung to the forward ends of the said arms and 120 provided with cultivating means, a tongue connected to the said transverse beam, and an adjusting-lever mounted on the frame and connected to the said tongue, as and for the purposes described.

In testimony whereof I affix my signature in presence of two witnesses.

HARLAN SMITH HOWARD.
